EXPANSION VALVE

Alwin B. Newton, Minneapolis, Minn., assignor to
 Minneapolis-Honeywell Regulator Company,
 Minneapolis, Minn., a corporation of Delaware

Application August 8, 1938, Serial No. 223,601

7 Claims. (Cl. 62—8)

This invention relates to expansion valves for use in refrigeration systems and more particularly in thermostatic expansion valves of the diaphragm type.

One of the objects of this invention is the provision of a diaphragm type expansion valve of simple but rugged construction and which is so designed that it may maintain a constant value of superheat at the outlet of the evaporator of the refrigeration system.

Another object of the invention is the provision of a diaphragm type thermostatic expansion valve wherein the diaphragms are so constructed that flexure thereof during operation of the valve does not affect the characteristics of the valve.

Another object of the invention is the provision of a thermostatic expansion valve of the type above described wherein the diaphragms may be constructed of rubber or like material and are so arranged that they are not subject to deterioration or rupture through long periods of use.

Other objects and advantages of the invention may become apparent to those skilled in the art upon reference to the specification, claims and accompanying drawings wherein like reference characters represent like parts in the various views; and wherein

Figure 1 is a view in cross section of one form of expansion valve embodying my invention and operatively connected in a refrigeration system.

Figure 2 is a cross section of another form of expansion valve embodying my invention.

Figure 3 is a cross sectional view of a still further modification of expansion valve embodying my invention, and

Figure 4 is a cross sectional view of a modification of a detail of the valve illustrated in Figure 3.

Referring more particularly to Figure 1, an expansion valve generally indicated by the reference character 10 is shown operatively connected to a refrigeration system, this system being of conventional form and including a compressor 11 having its high pressure side connected by means of a pipe 12 with a condenser 13 emptying into a receiver 14, the outlet of the receiver being connected by a pipe 15 to the inlet 16 of the expansion valve. The outlet 17 of the expansion valve communicates with the inlet of the evaporator 18 and the outlet of the evaporator communicates by means of pipe 19 with the inlet of compressor 11. The operation of the system is well understood by those skilled in the art and further description thereof is believed to be unnecessary.

The expansion valve 10 comprises casing members 22 and 23 which form valve chamber 24 and

the operating chamber 25. The sections 22 and 23 are suitably connected together in any well known manner, there being sealing means 26 for preventing the escape of refrigerant from the interior of the chambers and the chambers 24 and 25 communicate with one another by means of a passageway 30 formed in the inner wall 31 of the casing section 23. Pivoted within a recess 33 of the wall of the casing section 22 is a lever 35 carrying a valve element 36 which cooperates with a seat 37 which may be removable as illustrated and a spring 38 seated in a recess 39 in the wall of casing section 22 abuts against the arm 40 of the lever 35 and biases the valve element 36 into seating engagement with the valve seat 37. Refrigerant enters the valve chamber at 16 and the spaces 24 and 25 will be filled with comparatively warm refrigerant and the valve element 36 controls the expansion and flow of this refrigerant into the evaporator 18 as will be understood.

The operation of the lever 35 is controlled by a pair of diaphragms 42 and 43 which are rigidly connected together at their central portions by means of an apertured rod 44. The diaphragm 43 is rigidly held between a shoulder 46 in the wall of the casing section 22 by means of an annular member 47 held in place by means of the plate 48 suitably secured to the bottom of the casing section 23, there being a sealing gasket 49 between this plate and the casing to prevent any leakage of refrigerant therefrom. In a similar manner the diaphragm 42 is held against shoulder 55 by means of the member 56 which is in turn held in place by means of the plate 57 suitably secured to the casing section 23 and having sealing means 58 positioned between the plate and casing section to prevent escape of refrigerant therefrom.

The space below the diaphragm 43 communicates with the outlet of the evaporator by means of a pipe 60 connected at one end to the wall 48, its other end being flared and held by means of a nut 62 in engagement with the member 63 which may be threaded into the outlet of the evaporator or otherwise suitably secured thereto. It should now be apparent that the pressure within the space below the diaphragm 43 will be the same as the pressure at the outlet or the suction side of the evaporator 18.

The passageway in the rod 44 communicates at its upper end with the space formed between the diaphragm 42 and the upper plate 57 and the lower end of this passageway communicates with a capillary tube 66 which terminates in a bulb 67 located within the outlet of the evapora-

tor. This tube, bulb, and the space above the diaphragm 42 may be provided with a suitable volatile fill which may be the same substance as the refrigerant used in the system and therefore the pressure in the space above the diaphragm 42 will be the same as the pressure corresponding to the temperature of the refrigerant leaving the evaporator 18. The diaphragm 43 will tend to move upwardly as the pressure in the outlet of the evaporator increases and thus move the rod 44 and a pin 70 carried thereby upwardly in response to an increase in pressure. The pin 70 limits the movement of the valve 36 toward its closed position under the influence of the biasing spring 39 since the extremity of the lever 35 is held against this pin. Accordingly as the pin moves downwardly the valve element 36 will move towards open position against the force of the spring 38. As the temperature of the refrigerant leaving the outlet of the evaporator increases the pressure in the space above the diaphragm 42 will increase and move this diaphragm downwardly which will tend to open the valve 36. It will therefore be seen that the position of the pin 70 and consequently of the valve 36 will depend both upon the pressure of the refrigerant at the outlet of the evaporator and also upon the temperature of the refrigerant, or in other words, upon the superheat of the refrigerant at the evaporator outlet.

It is a characteristic of all known refrigerants that as the temperature of the refrigerant increases the pressure corresponding to the temperature increases at a greater rate so that the pressure exerted upon the diaphragm 42 tending to open the valve will not vary in a straight line relationship with the temperature. The result of this is that if the effective areas of the diaphragms are equal the superheat existing at the evaporator outlet will vary in accordance with variations in temperature of the refrigerant at the evaporator outlet. As the superheat at the outlet increases the effective cooling area of the evaporator decreases and it is desirable to use as much of the evaporator at all times as is possible for cooling in order that the system may operate at maximum efficiency. In order to do this the superheat at the outlet of the evaporator should be kept substantially constant at all times and one way of accomplishing this is by making the effective area of the diaphragm 42 which is exposed to the pressure corresponding to the temperature at the evaporator outlet less than the effective area of the other diaphragm by an amount which is sufficient to compensate for the deviation of the temperature pressure curve of the refrigerant from a straight line relationship.

This is accomplished by the provision of a sealing bellows 75 which is suitably connected to the upper portion of the rod 44, the lower end 60 of this sealing bellows being suitably secured to a cup-shaped member 76 which is in turn secured to the upper plate member 57. This sealing bellows thus serves the purpose of permitting movement of the rod 44 with the diaphragms 42 and 43 while preventing escape of refrigerant from the upper chamber or preventing entrance of air into this chamber around the rod and at the same time it reduces the area of the diaphragm 42 since the pressure within this upper chamber 70 above the diaphragm will act upwardly on the bellows 75 and thus decrease the effective area of the diaphragm 42 by an amount which is equal to the area of the bellows 75.

Threaded to the upper extremity of the rod 75 75

is an adjusting nut 78 against which bears a compression spring 79, the lower end of this spring bearing against the plate 80 which is rigid with the top plate 57 of the casing 23. This spring tends to urge the rod 44 upwardly and the valve towards closed position and thus opposes the opening action of the diaphragm 42. By properly adjusting this spring 79 in accordance with the size of the bellows 75 the superheat which is maintained at the outlet of the evaporator will be maintained substantially constant. If it is desired to vary the amount of superheat that is maintained this may be done by suitable adjustment of the nut 78 although this adjustment will have the effect of causing variations in superheat at the evaporator outlet as the pressure and temperature varies therein, although the amount of this deviation will be slight for a small adjustment of the spring 79.

It will now be understood that as the pressure of the refrigerant leaving the evaporator rises the diaphragm 43 tends to move upwardly and the valve moves towards closed position but as the temperature of the refrigerant leaving the evaporator increases the diaphragm 42 will move downwardly causing an opening movement to be imparted to the valve thus permitting flow of more refrigerant into the evaporator 18 and in this manner the valve is properly positioned to maintain the desired degree of superheat at the outlet of the evaporator.

Referring now to Figure 2, an expansion valve is illustrated which operates in the same manner as the valve of Figure 1 but having a somewhat different construction. In this form of the invention the valve casing 22 is shown as being positioned below the casing 23.

The valve 90 is vertically movable and includes a stem 91 slidable within a boss 92 projecting downwardly from the top wall 93 of the casing 22. A spring 94 positioned between the wall 93 and the valve element 90 urges this valve into closed position. Positioned at each side of the valve are levers 95 which may be fulcrumed about knife edges 96, these levers having their inner ends positioned below the circular flange 97 of the valve 90 and their outer ends being connected to rods 98 which extend through openings 99 in the wall 93 and having their upper ends abutting the operating structure 101. The biasing spring 94 besides urging the valve towards closed position also urges the outer portions of the levers 95 upwardly so that the upper ends of the rods 98 are held in engagement with the underside of the structure 101. Sealing bellows 103 suitably secured to the rods 98 and having their other ends secured to the wall 93 of the casing 22 prevent the flow of refrigerant into the interior of the casing 23.

The operating structure for the valve comprises a pair of rubber diaphragms or diaphragms of similar material 105 and 106 which are suitably held against a piston member 107 by means of the plates 108 and 109 which are in threaded engagement with extensions of the piston 107 and serve to clamp the diaphragms between the piston and the plates. A ring shaped member 112 clamps the diaphragm 106 into engagement with shoulders 113 in the wide walls of the casing 23 and a second member 116 which forms the top wall of the casing 23 has a cylindrical portion 117 which serves to hold the diaphragm 105 into engagement with the upper portion of the ring shaped member 112. Suitable cut-out portions 120 formed in the casing

23, the ring shaped member 112, and the extension 117 of the top wall 116 are provided to permit flexing of the diaphragms 105 and 106.

The piston 107 and its threaded extensions are provided with a passageway 125 which communicates with the space formed between the plate 108 and the top wall 116 and the lower end of this passageway is connected to the capillary tube 127 having its other end connected with a bulb mounted in the outlet of the evaporator as in Figure 1. The pipe 130 connects the outlet of the evaporator with the space below the plate 109 in the same manner as in Figure 1.

The end of the upper projecting portion 134 of the piston 107 terminates in the threaded portion 135 which carries an adjusting nut 78 to vary the tension of the compression spring 79 having its lower portion resting upon a plate 80 as in Figure 1. Sealing bellows 75 connected to the rod 134 and having its lower end connected to the cup-shaped member 76 acts in the same way as in Figure 1 to decrease the effective area of the upper portion of the assembly 101 and at the same time seals the rod 134 while at the same time permitting movement thereof.

Shoulders 140 and 141 provided in the vertical walls of the casing 23 and in the upper member 116 limit the movement of the piston 107 and therefore the amount of flexing of the diaphragms 105 and 106. While ordinarily, during the operation of this valve, there will be very slight movement of the structure 101, these shoulders prevent any extensive movement thereon should this occur through any abnormal circumstances.

In operation this valve will function in the manner similar to that of Figure 1, the structure 101 moving downwardly as the pressure above the plate 108 increases by reason of an increase in temperature of the refrigerant at the evaporator outlet, this movement causing the inner ends of the levers 95 to move upwardly thus opening the valve 90. As the pressure of the refrigerant at the evaporator outlet increases the pressure below the plate 109 will increase and urge the assembly 101 upwardly whereupon the valve 90 will move towards closed position under the influence of the biasing spring 94. The provision of the sealing bellows 75 insures the maintenance of a constant degree of superheat at the evaporator outlet as in Figure 1.

The space in the casing section 22 must be sealed in the casing 23 in this figure to prevent the pressure of the entering refrigerant from acting upwardly on the operating assembly 101. This sealing of the two chambers was not necessary in Figure 1 since the entering refrigerant acts equally but in opposite directions upon the diaphragms 42 and 43 and thus would have no effect upon the operation of the valve 36. One advantage of using rubber-like diaphragms in place of metallic diaphragms as in Figure 1 is that the metal diaphragms exert an increasing force opposing the flexure thereof as the diaphragms become flexed to a greater degree but in the case of the diaphragms of Figure 2 this will make little or no difference in the operation of the valve.

Referring now to Figure 3 the valve illustrated is generally similar to that of Figure 1 except that the sealing bellows 75 is omitted in this form of the invention. The space below the diaphragm 43 communicates with the capillary tube 68 leading to the bulb 67 so that

upon an increase in temperature of the refrigerant at the evaporator outlet the diaphragm 43 moves upwardly. The extremity of the lever 35 is positioned above the movable abutment 70 and the position of the valve 36 and the spring 38 is shown reversed from that of Figure 1. Accordingly as the lever 35 moves upwardly in response to an increase in temperature of refrigerant at the outlet of the evaporator the valve 36 moves towards open position. The pipe 60 which connects with the outlet of the evaporator is connected to a pipe 150 which in turn communicates with the passageway through the member 151 which connects the diaphragms 42 and 43 together, this passageway opening into the space above the diaphragm 42 so that as the pressure of the refrigerant at the outlet of the evaporator increases the diaphragm 42 will be urged downwardly thus permitting movement of the valve 36 towards closed position under the influence of the biasing spring 38.

The rod 151 which connects and separates the diaphragms 42 and 43 does not extend outwardly from the top wall 157 of the casing but terminates within the space between the diaphragm 42 and the top wall 157. Threaded within the top wall 157 is an adjusting screw 158 which is sealed by means of a suitable packing gland 159 in the top wall 157. A compression spring 165 is connected between the cup-shaped members 166 and 167 held against the opposing ends of the screw 158 and the member 151, respectively. This spring tends to move the connecting member 151 downwardly or in a position to permit the closing of the valve 36 and in this manner opposes the opening movement of the diaphragm 43 which is exposed to a pressure corresponding to the pressure of the refrigerant at the outlet of the evaporator. The adjustment of the spring 165 is readily effected by turning the adjusting screw 158 as is readily apparent and a cover member 170 screw threaded over the projecting portion 171 of the plate 157 serves to protect the upper end of the screw 158 and to prevent unauthorized tampering therewith.

In this form of the invention the spring 165 is housed entirely within the valve structure and there is no member projecting outwardly from the casing which is constantly moved as the valve changes position. The arrangement of Figures 1 and 2 however has the advantage that movement of the expansion valve is readily ascertained by watching the movement of the adjusting nut 78 and also in these first two figures the use of the sealing bellows provides for the maintenance of a constant degree of superheat.

A modification of the structure shown in Figure 3 is illustrated in Figure 4 wherein the upper end of member 151 projects through the top wall 157 of the casing and screw threaded to the exterior of the plate 157 is a cup-shaped adjusting member 180 forming an abutment for a compression spring 181 having its lower end seated on the spring retainer 182 fitted on the end of the member 151. The member 151 will move with the diaphragm assembly but the upward movement of this member which corresponds to the opening of the expansion valve is opposed by the spring 181 and the force of this spring is readily adjusted by the member 180. The adjusting member 180 may be concealed and protected by means of the cover 185 screw threaded to the wall 157 as illustrated. A suitable packing gland 187 is provided for sealing the rod 151 and the plate 157 together. It will be readily apparent that this adjusting

means may be substituted for the adjusting means of Figure 3 if it is desired to have the compression spring 165 of Figure 3 outside of the casing as in Figure 4, the operation of the valve being in no way affected by this modification.

Having described the preferred forms of my invention many modifications may become apparent to those skilled in the art and I wish it to be understood that my invention is limited only by the scope of the appended claims.

I claim as my invention:

1. In a refrigeration system including an evaporator, means for controlling the flow of refrigerant into the evaporator, said means comprising a valve body divided by an apertured wall into a valve chamber and an operating chamber, said valve chamber having an inlet and an outlet through which refrigerant flows on the way to the evaporator, a valve member in said valve chamber for controlling the flow of refrigerant from the inlet to the outlet, a diaphragm structure including a pair of diaphragms in said operating chamber spaced from the top and bottom thereof and spaced from one another, means clamping the edges of said diaphragms to the wall of said operating chamber and means rigidly connecting the central portions of said diaphragms together, said connecting means having a passageway therethrough, means extending through the aperture in said wall operatively connecting said diaphragm structure to said valve member, a pair of pressure communicating means connected to a wall of said operating chamber opposite one of said diaphragms, one of said pressure communicating means opening into the space opposite said one diaphragm, the other of said pressure communicating means being connected through the passageway in said rigid connecting means to the space opposite said other diaphragm, means connecting one of said pressure communicating means to the outlet of the evaporator, and means connecting the other of said pressure communicating means to a bulb exposed to the temperature of the refrigerant leaving the evaporator, said bulb having a volatile fill.

2. In a refrigerating system including an evaporator, means for controlling the flow of refrigerant to the evaporator, said means comprising a valve body separated by an apertured wall into a valve chamber and an operating chamber, said valve chamber including an inlet and an outlet, a valve member in said valve chamber for controlling the flow of refrigerant from the inlet to the outlet, an operating arm for controlling the position of said valve member and extending through the aperture in said wall, a member in said operating chamber movable in response to variations in superheat at the evaporator outlet, said member comprising a pair of parallelly arranged diaphragms having their adjacent sides rigidly connected together at their centers and having their edges rigidly secured to the walls of the chamber, means providing an operative connection between said member and said operating arm, means exposing the other side of one of said diaphragms to a pressure corresponding to the temperature of the refrigerant at the evaporator outlet, means exposing the other side of said other diaphragm to the pressure on the suction side of the refrigeration system, means biasing said valve towards closed position, said means being located on the exterior of said casting, and means for varying the biasing effect of the biasing means.

3. In a refrigerating system including an evaporator, means for controlling the flow of refrigerant to the evaporator, said means comprising a valve body separated by an apertured wall into a valve chamber and an operating chamber, said valve chamber including an inlet and an outlet, a valve member in said valve chamber for controlling the flow of refrigerant from the inlet to the outlet, an operating arm for controlling the position of said valve member and extending through the aperture in said wall, a member in said operating chamber movable in response to variations in superheat at the evaporator outlet, said member comprising a pair of parallelly arranged diaphragms having their adjacent sides rigidly connected together at their centers and having their edges rigidly secured to the walls of the chamber, means providing an operative connection between said member and said operating arm, means exposing the other side of one of said diaphragms to a pressure corresponding to the temperature of the refrigerant at the evaporator outlet, means exposing the other side of said other diaphragm to the pressure on the suction side of the refrigeration system, means biasing said valve towards closed position, and means rendering the effective operating area of the diaphragm exposed to the pressure corresponding to the temperature of the refrigerant at the outlet of the evaporator less than the effective operating area of the other diaphragm by an amount sufficient to insure the maintenance of a substantially constant degree of superheat at the evaporator outlet.

4. In a refrigerating system including an evaporator, means for controlling the flow of refrigerant to the evaporator, said means comprising a valve body separated by an apertured wall into a valve chamber and an operating chamber, said valve chamber including an inlet and an outlet, a valve member in said valve chamber for controlling the flow of refrigerant from the inlet to the outlet, an operating arm for controlling the position of said valve member and extending through the aperture in said wall, a member in said operating chamber movable in response to variations in superheat at the evaporator outlet, said member comprising a pair of parallelly arranged diaphragms having their edges rigidly secured to the walls of the chamber and means forming a rigid connection between the centers of the diaphragms, means providing an operative connection between said member and said operating arm, means exposing the other side of one of said diaphragms to a pressure corresponding to the temperature of the refrigerant at the evaporator outlet, and means exposing the other side of said other diaphragm to the pressure on the suction side of the refrigeration system, said last named means including the means forming the connection between said diaphragms.

5. In a refrigeration system including an evaporator and valve means for controlling the flow of refrigerant to the evaporator, said valve means comprising a valve member and a cooperating valve seat, means for controlling the position of the valve member with respect to said seat comprising a diaphragm assembly including a pair of diaphragm members of flexible material parallelly arranged and rigidly connected together, a chamber housing said diaphragm members with the members suitably secured to the walls of said chamber, means connecting said diaphragm assembly with said valve member, means exposing one side of said diaphragm assembly to the pres-

sure on the suction side of the refrigeration system, means exposing the other side of said diaphragm assembly to the pressure corresponding to the temperature of the refrigerant at the evaporator outlet, means biasing said valve member towards closed position, and means rendering the effective operating area of said other side of said diaphragm assembly less than the effective operating area of said one side of said diaphragm assembly by an amount sufficient to insure the maintenance of a substantially uniform degree of superheat at the evaporator outlet.

6. In a refrigeration system, including a compressor and an evaporator, valve means for controlling the flow of refrigerant into the evaporator, said means comprising a casing divided into a valve chamber and an operating chamber, said valve chamber including an inlet and an outlet, a valve member in said valve chamber controlling the flow of refrigerant from the inlet to the outlet, the operating chamber having a piston slideable therein, means sealing said piston to the sides of said operating chamber, means operatively connecting said piston and said valve member, means exposing one side of said piston to the pressure on the suction side of the refrigeration system, and means subjecting the other side of said piston to a pressure corresponding to the temperature at the outlet of the evaporator.

7. In a refrigeration system including an evaporator and valve means for controlling the flow of refrigerant to the evaporator, said valve means comprising a valve member and a cooperating valve seat, means for controlling the position of the valve member with respect to said seat comprising a diaphragm assembly including a pair of diaphragm members of rubber-like material parallelly arranged and rigidly connected together, a chamber housing said diaphragm members with the members suitably secured to the walls of said chamber, means connecting said diaphragm members with said valve member, means exposing one side of said diaphragm assembly to the pressure on the suction side of the refrigeration system, means exposing the other side of said diaphragm assembly to the pressure corresponding to the temperature of the refrigerant at the evaporator outlet, means limiting movement of the diaphragm members in either direction to prevent rupture thereof, means biasing said valve member towards closed position, and means reducing the effective operating area of said other side of said diaphragm assembly by an amount sufficient to insure the maintenance of a substantially uniform degree of superheat at the evaporator outlet.

ALWIN B. NEWTON.
